UNITED STATES PATENT OFFICE

2,448,057

CUTTINGS CONVEYING MECHANISM

Leon E. Simmons, Claremont, N. H., assignor to
 Joy Manufacturing Company, a corporation of
 Pennsylvania

Application October 9, 1943, Serial No. 505,609

12 Claims. (Cl. 262—30)

1

This invention relates to cuttings conveying mechanism, and more particularly, but not exclusively, to improvements in a cuttings conveying mechanism especially designed for use with a room and pillar type coal cutting machine.

Modern high-speed coal cutting machines of the room and pillar type have a relatively large cutting capacity, and during the kerf cutting operation a relatively large quantity of cuttings, created by the cutters of the cutter chain, accumulate so rapidly at the rear of the cutter bar that it is practically impossible for the shovelers to remove them. The cuttings, therefore, pile up rapidly around the rear end of the machine in such a manner as to reduce the cutting efficiency and to hinder proper setting of roof props. Known attempts have been made mechanically to remove the cuttings from the vicinity of the cutter chain of a room and pillar coal cutting machine, but such mechanisms are relatively bulky, greatly increase the longitudinal dimension of the machine, preventing close setting of roof props, and, due to their design, are relatively noisy in operation and create considerable objectionable dust.

It is an object of the present invention to provide an improved cuttings conveying mechanism especially designed for use with a modern high-speed room and pillar coal cutting machine for overcoming the disadvantages of conveying means of known types. It is another object to provide a cuttings conveying mechanism of relatively large capacity and which is comparatively noiseless in operation and creates a minimum of dust. A further object is to provide an improved cuttings conveyor mechanism of comparatively large capacity which is extremely compact. Still another object is to provide an improved cuttings conveying mechanism adapted for attachment to a conventional coal cutting machine and adapted to be driven by the machine motor. A still further object is to provide an improved cuttings conveying mechanism embodying coacting conveying devices which serve to move relatively large quantities of cuttings from the vicinity of the cutter chain. Yet another object is to provide an improved cuttings conveying mechanism embodying a pair of coacting conveying devices arranged in parallel relation on upright axes at the rear end of a room and pillar coal cutting machine, and which serve to gather the cuttings and move and eject them rearwardly with respect to the machine. Still another object is to provide an improved cuttings conveying mechanism which may be readily applied to a conventional

2

coal cutting machine with a minimum of modification of the machine. Other objects and advantages of the invention will, however, hereinafter more fully appear.

5 In the accompanying drawings there is shown for purposes of illustration one form which the invention may assume in practice.

In these drawings:

Fig. 1 is a plan view of a coal cutting machine 10 with which an illustrative form of the improved cuttings conveying mechanism is associated.

Fig. 2 is a side elevational view of the coal cutting machine and conveying mechanism shown in Fig. 1.

15 Fig. 3 is an enlarged rear end elevational view of the cutting machine and conveying mechanism shown in Figs. 1 and 2, with the upper portion of the machine broken away to facilitate illustration.

Fig. 4 is an enlarged cross sectional view taken 20 substantially on line 4—4 of Fig. 6.

Fig. 5 is an enlarged view in longitudinal vertical section taken substantially on line 5—5 of Fig. 1.

Fig. 6 is an enlarged horizontal sectional view 25 taken substantially on line 6—6 of Fig. 2.

Fig. 7 is a horizontal sectional view taken substantially on line 7—7 of Fig. 5, with parts shown in a different position.

Fig. 8 is a horizontal sectional view taken substantially on line 8—8 of Fig. 5.

Fig. 9 is a detail sectional view taken substantially on line 9—9 of Fig. 5.

Fig. 10 is a detail sectional view taken substantially on line 10—10 of Fig. 6.

35 Fig. 11 is a fragmentary side elevational view, showing the cuttings-conveying mechanism detached from the coal cutting machine.

Fig. 12 is a view similar to Fig. 7 on a reduced scale, showing the eccentric gathering portions 40 arranged so as to traverse their cycles oppositely but in step.

In this illustrative embodiment of the invention, the improved cuttings conveying mechanism, generally designated 1, is associated with 45 a coal cutting machine of the flexibly fed, room and pillar, floor cutter type, generally designated 2. The coal cutting machine shown is of a conventional design and may be similar to that disclosed in Patent No. 2,131,178 patented 50 Sept. 27, 1938, in which I am one of the joint inventors. Evidently, the improved cuttings conveying mechanism may be associated with coal cutting machines of other types.

The coal cutting machine 2 as disclosed herein 55 comprises a machine frame 3 mounted on a bot-

tom plate or shoe 4 slideable on the floor of a mine. Extending longitudinally throughout the length of the lower portion of the machine frame is a chamber 5 having arranged therein and secured to the machine frame, the rearward portion of an elongated horizontal plane cutter bar 6, the latter having guided on its margin for circulation thereabout an endless cutter chain 7. The flexible feeding means of the machine may comprise feeding and controlling drums 8 and 9 arranged at the opposite sides of the machine frame and respectively having wound thereon feeding and controlling cables 10 and 11. Carried by the machine frame is a motor 12 having its power shaft operatively connected to the cutter chain and to the feeding and controlling drums for effecting drive thereof. As shown in Fig. 14 of the patent above referred to, the motor power shaft is connected through spur and bevel gearing to a vertical shaft and a corresponding shaft is herein designated 13 (Fig. 6) and is keyed to a chain sprocket 14 arranged in the chamber 5 and engaging and driving the endless cutter chain 7. As shown in Figs. 14 and 15 of the patent above referred to, the motor power shaft is operatively connected through spur and bevel gearing to the feeding and controlling drums to effect independent drive of the latter at either relatively high or relatively low cable winding speeds. In Fig. 5 herein, a portion of the high and low speed gearings for one of the drums is shown. A high-speed gear 15 is connectible by a multiple disk clutch 16 to a horizontal shaft 17 which extends longitudinally of the machine and is suitably journaled in the machine frame. Driven by this shaft is a worm 18 meshing with a worm wheel 19 which is connectible by a multiple disk clutch 20 to a horizontal transversely extending shaft 21, the latter being operatively connected to one of the cable winding drums, herein the controlling drum 9. A low-speed gear 22, coaxial with the gear 15, is connectible by a multiple disk clutch 23 to the shaft 17. The clutches 16 and 23 have suitable operating means so that when one of them is applied, the other is released. It is accordingly evident that the worm shaft 17 may be driven selectively at high and low speeds through the gears 15 and 22.

The feeding and controlling cables 10 and 11 may be extended from the feeding and controlling drums 8 and 9 around appropriately located guide sheaves on the machine in a conventional manner and may be connected at their free ends to suitable anchor jacks located at the rib and face of the room of a mine. The cutter chain 7 when connected in driving relation with the motor may be rapidly circulated about the margin of the cutter bar, and, as the cables are wound in by the motor driven drums the cutter bar may be sumped beneath the coal at one rib, thereafter be fed transversely across the coal face, to cut a horizontal kerf beneath the coal, and finally be withdrawn from the face at the opposite rib. The feeding drum effects feed of the machine and the controlling drum controls the angle of the machine with respect to the coal face during the kerf cutting operation in the manner well known to those skilled in the art. During the kerf cutting operation, the cuttings created by the cutters of the cutter chain are carried back from the kerf through the chamber 5 extending through the lower portion of the machine frame for discharge at the rear end of the machine. Since the mode of operation of a room and pillar coal cutting machine of the type disclosed is well

known and is fully described in the patent referred to, further description thereof is herein unnecessary.

The improved cuttings conveying mechanism is attached to the rear end of the coal cutting machine and is arranged in such manner that its conveying devices remove the cuttings from the vicinity of the cutter chain at the rear end of the chamber 5 and convey the cuttings to discharge rearwardly of the machine out of the machine path. Now referring to the specific structure of the cuttings conveying mechanism, it will be noted that arranged in a casing 25 are coacting conveying devices 26 and 27 herein preferably arranged in parallel offset relation on upright axes. The axes of the conveyor devices lie in a common transverse vertical plane, as shown in Figs. 6 and 7. These conveyor devices are arranged in a horizontal chamber 28 in the casing 25 and when the conveyor casing is attached to the cutting machine in the manner shown, the chamber 28 communicates directly with the rear end of the chamber 5 so that the cuttings moved rearwardly by the cutter chain are discharged into the casing chamber. The conveyor devices 26 and 27 preferably revolve in relatively opposite directions and each comprises a flat horizontal circular disk or plate 29 arranged with its bottom surface substantially flush with the casing bottom and having an upstanding portion 30, cylindrical except as later described and illustrated, arranged eccentrically with respect to the axis of rotation of the disk. The bottom of the conveyor casing is cut away intermediate the disks at its rearward portion. As shown in Fig. 5, each disk has coaxial lower and upper shaft portions 31 and 32 suitably journaled within the conveyor casing. The eccentric portion 30 of each disk is arcuately cut away or recessed at 33 at its opposite sides to provide a relatively narrow vertical gathering portion 34, and formed above this recessed portion is a circular bearing portion 34' surrounded by an annular strap 35. This strap is mounted for oscillatory movement with respect to the disk-eccentric and has projecting lugs 36 to which a pusher arm 37 is pivotally connected at 38. This pusher arm is pivotally mounted at 39 on a vertical pivot pin 40 supported by the conveyor casing at one side of the latter. Mounted on a pivot pin 41, providing the pivot 38, is a scraper shoe 42 which extends vertically of the eccentric-recesses and slidably engages a circular portion 43 at the bottom of the eccentric. As the cuttings are moved into the casing chamber 28 by the cutter chain, they are received by the disks and as the latter revolve, the eccentric gathering portions 34 of the disks engage the cuttings and move them rearwardly within the casing chamber and the cuttings so moved are deflected by the shoes 42 toward the pusher arms 37 and the latter positively eject the cuttings rearwardly from the casing chamber. It is accordingly evident that the cuttings are continuously gathered, conveyed and ejected rearwardly of the conveyor casing with the creation of a minimum of dust and comparatively noiselessly.

The conveyor casing has its bottom section attached by screws 43 to the rear end of the machine frame of the cutting machine and has lip portions or feet 44 overlying and resting on the bottom of the skid plate of the machine, and the conveyor casing is suitably fitted to the rear end of the machine in an extremely compact manner. An upper gear housing 45 is releasably attached to the bottom casing section by screws 46 and

this housing may be readily detached to obtain access to the internal mechanism. Arranged between the gear housing and the bottom casing section is a horizontal cover plate 47 held into position by screws 48 and which may also be readily removed.

The conveyor driving means may assume various forms and herein comprises a shaft 50 (Fig. 5) extending centrally through a bore in the worm shaft 17 and keyed at its forward end to a shaft 51 in turn keyed to the hub of the gear 15 and driven by the latter. The shaft 50 is clutched at 52 at its rear end to the hub of a cone 53 of a frictional cone clutch. The cone 53 is held by a spring 54 in frictional engagement with the walls of a conical bore 55 formed in a clutch member 56. This clutch member is suitably journaled within the machine frame and has its hub clutched at 57 to a horizontal longitudinally extending shaft 58 herein having its rearward portion enclosed within a tubular housing 59 suitably detachably secured at its inner end to the rear end of the machine frame. The rear end of the tubular housing 59 is provided with an annular portion which is slidably received within a bore 60 in the gear housing 45 of the conveyor. The rear end of the shaft 58 is suitably journaled within the gear housing 45 and has formed thereon a bevel gear 61 meshing with a bevel gear 62 having its hub keyed to a clutch member 63 journaled on a bearing sleeve supported by a vertical shaft 64. The shaft 64 is journaled within the gear housing 45 and has splined thereto at 65 a shiftable clutch member 66 having clutch teeth engageable with clutch teeth on the clutch member 63. Engaging the clutch member 66 is a shipper yoke 67 having a suitable operating handle 68 (see Fig. 9). It is accordingly evident that when the clutch 66 is connected the gear 62 is in driving relation with the shaft 64. The splined connection at 65 between the sliding clutch and the shaft is herein in the form of a spring pressed pawl 69 mounted on the shaft 64 and engaging with a notch 70 formed on the clutch hub so that the shaft is driven by the bevel gear through this pawl. Formed on the lower portion of the vertical shaft 64 is a spur gear 71 meshing with a spur gear 72 having its hub keyed at 73 to the upper shaft portion 32 of one of the revolving disks.

The key connection between the gear hub and the hub portion 32 includes a segmental block 74 having a plane surface abutting a plane surface 75 on the shaft portion and having a vertical key slot for receiving a key 76. The gear hub is also slotted to receive the key. As shown in Fig. 8 the gear 72 meshes with and drives a spur gear 77 which meshes with a spur gear 78, the latter in turn meshing with and driving a spur gear 79 having a key connection at 80 similar to the key connection above described, with the upper shaft portion of the other revolving disk. It is accordingly evident that the conveying disks may be driven through the spur gears 71, 72, 77, 78 and 79 at the same speed in relatively opposite directions.

In the event that it is desired to reverse the direction of orbital movement of the cutter chain during the kerf cutting operation, the pawl 69, shown in Fig. 9, slips out of the notch 70 disconnecting the conveyor devices from the machine motor. Thus, the pawl prevents reverse rotation of the conveyor devices thereby eliminating the possibility of the devices becoming clogged and jammed when the cutter chain is

reversed. The frictional cone clutch, in the conveyor drive, is set at a predetermined load to slip automatically in the event that the conveyor devices become overloaded thereby to prevent damage to the parts.

The disks 29 are so set in assembling the device that a relatively wide space will be insured above the disks between the eccentrics, thereby enabling large pieces of coal or other material to be ejected from the casing chamber. In other words, the arrangement is such that the portions 34 can never both be pointing directly towards the other at the same time, but instead there is always between them a space at least approximately as wide as the length of either of them between its axis of turning and its radially outer end. The gathering eccentrics, as the disks revolve, serve to move the cuttings rearwardly within the casing chamber, and the cuttings are moved by the eccentrics from one disk towards the other, and the pusher arms 37 which receive the cuttings serve to push the cuttings rearwardly from the disks positively to eject the cuttings from the casing chamber at the rear end of the machine. It will be evident that instead of arranging the disks with their eccentric gathering portions so that they move as above described, the same may be arranged, as shown in Fig. 12, so that they move in such a manner, as to traverse their cycles oppositely but in step, passing through their points of closest adjacency to each other at the same time. The conveyor mechanism may be readily detached from the coal cutting machine simply by removing the screws 43 and moving the conveyor mechanism bodily in a rearward direction into the position shown in Fig. 11, the drive connections between the conveyor devices and the machine gearing releasing automatically at the clutch 57 as the conveyor mechanism is so moved. As the conveyor mechanism is moved rearwardly the annular portion of the tubular housing 59, is separated from the bore 60.

As a result of this invention an improved cuttings conveyor mechanism is provided which overcomes the disadvantages of known types of cuttings conveyors. It will be noted that by the provision of coacting conveyor devices arranged and operating in the manner disclosed, relatively large quantities of cuttings may be conveyed from the vicinity of the cutter chain of a modern high-speed coal cutting machine. It will also be evident that by the provision of the coacting conveyor devices, it is possible not only effectively to remove large quantities of cuttings from the machine, but also relatively large pieces of coal or other material may move freely past the conveyor devices without jamming. The conveyor devices, due to their design will operate relatively quietly, and create comparatively little objectionable dust, and be extremely compact enabling relatively close setting of roof props. By the provision of the ratchet drive for the conveyor devices, the latter are automatically disconnected from the machine motor in the event the cutter chain is reversed, thereby to prevent possible damage to the conveyor mechanism. Other advantages of the improved conveyor mechanism will be clearly apparent to those skilled in the art.

While there is in this application specifically described one form which the invention may assume in practice, it will be understood that this form of the same is shown for purposes of illustration, and that the invention may be modified and embodied in various other forms without

departing from its spirit or the scope of the appended claims.

What I claim as new and desire to secure by Letters Patent is:

1. A cuttings-conveying mechanism adapted for association with a coal cutting machine of the kind having orbitally moving kerf cutting devices guided for circulation in a cuttings-receiving chamber within the frame of the machine, comprising a casing attachable to the machine frame of the coal cutting machine and having a chamber for receiving the cuttings brought back from the kerf by the cutting devices and discharged from said machine-frame chamber, and cuttings-moving and ejecting means in said casing chamber for moving the cuttings rearwardly therein and for positively ejecting the cuttings therefrom, said moving and ejecting means including a cuttings-moving member movable orbitally in said casing-chamber about an upright axis, a horizontally swingable cuttings-moving and ejecting element associated with said member and pivotally mounted at one end on said casing at one side of the latter and pivotally connected at its opposite end to said cuttings-moving member and means for rotating said member and for swinging said element horizontally back and forth on its pivotal mounting for causing said member to move the cuttings horizontally and rearwardly in said casing-chamber and said element to receive the cuttings from said member and move the cuttings rearwardly in and eject the cuttings so moved from said casing-chamber.

2. A cuttings-conveying mechanism adapted for association with a coal cutting machine of the kind having orbitally moving kerf cutting devices guided for circulation in said cuttings-receiving chamber within the frame of the machine, comprising a casing attachable to the machine frame of the coal cutting machine and having a chamber for receiving the cuttings brought back from the kerf by the cutting devices and discharged from said machine-frame chamber, and cuttings-moving and ejecting means in said casing-chamber for moving the cuttings rearwardly therein and for positively ejecting the cuttings therefrom, said moving and ejecting means including a horizontal table arranged at the bottom of said casing chamber for rotation about an upright axis, a cooperating horizontally swingable arm disposed above said table and pivotally mounted on said casing at one side thereof and means for rotating said table for moving the cuttings received thereby rearwardly in said casing chamber and for swinging said arm horizontally back and forth on its pivotal mounting for causing said arm to receive the cuttings from said table and move the cuttings rearwardly in and eject the cuttings so moved from said casing-chamber.

3. A cuttings-conveying mechanism adapted for association with a coal cutting machine of the kind having orbitally moving kerf cutting devices guided for circulation in a cuttings-receiving chamber within the frame of the machine, comprising a casing attachable to the machine frame of the coal cutting machine and having a chamber for receiving the cuttings brought back from the kerf by the cutting devices and discharged from said machine-frame chamber, and cuttings-moving and ejecting means in said casing-chamber for moving the cuttings rearwardly therein and for positively ejecting the cuttings therefrom, said moving and ejecting means including a horizontal table disposed at the bottom of said cas-

ing chamber for rotation about an upright axis for receiving the cuttings and having an upstanding eccentric portion, a cooperating horizontally swingable arm disposed above said table and pivotally mounted at one end on said casing at one side of the latter and pivotally connected at its opposite end to said eccentric portion, and means for rotating said table for causing said eccentric portion to move the cuttings received thereby rearwardly in said casing chamber and for swinging said arm horizontally back and forth on its pivotal mounting for causing said arm to receive the cuttings moved rearwardly by said eccentric portion and move the cuttings rearwardly in and eject the cuttings so moved from said casing-chamber.

4. A cuttings-conveying mechanism adapted for association with a coal cutting machine of the kind having orbitally moving kerf cutting devices guided for circulation in a cuttings-receiving chamber within the frame of the machine, comprising a casing attachable to the machine frame of the coal cutting machine and having a chamber for receiving the cuttings brought back from the kerf by the cutting devices and discharged from said machine-frame chamber, and cuttings-moving and ejecting means in said casing-chamber for moving the cuttings rearwardly therein and for positively ejecting the cuttings therefrom, said moving and ejecting means including a cuttings-moving and ejecting members pivotally mounted on said casing respectively at the sides thereof and projecting horizontally inwardly toward the opposite sides of said casing and means for swinging said members back and forth on their pivotal mountings horizontally in out-of-step relation in said casing-chamber for moving the cuttings rearwardly in and ejecting the cuttings so moved from said casing-chamber.

5. A cuttings-conveying mechanism adapted for association with a coal cutting machine of the kind having orbitally moving kerf cutting devices guided for circulation in a cuttings-receiving chamber within the frame of the machine, comprising a casing attachable to the machine frame of the coal cutting machine and having a chamber for receiving the cuttings brought back from the kerf by the cutting devices and discharged from said machine-frame chamber, and cuttings-moving and ejecting means in said casing-chamber for moving the cuttings rearwardly therein and for positively ejecting the cuttings therefrom, said moving and ejecting means including cuttings-gathering members arranged at the bottom of said casing-chamber to rotate about upright parallel axes respectively at the opposite sides of said casing-chamber, cooperating cuttings-moving and ejecting elements pivotally mounted on said casing respectively at the sides thereof and operatively connected to said gathering members for actuation in out-of-step relation thereby and means for rotating said gathering members to move the cuttings received thereby rearwardly in said casing-chamber and to cause said elements to swing back and forth in out-of-step relation on their pivotal mountings for moving the cuttings rearwardly in and ejecting the cuttings so moved from said casing-chamber.

6. A cuttings-conveying mechanism adapted for association with a coal cutting machine of the kind having orbitally moving kerf cutting devices guided for circulation in a cuttings-receiving chamber within the frame of the machine, comprising a casing attachable to the

machine frame of the coal cutting machine and having a chamber for receiving the cuttings brought back from the kerf by the cutting devices and discharged from said machine-frame chamber, and cuttings-moving and ejecting means in said casing-chamber for moving the cuttings rearwardly therein and for positively ejecting the cuttings therefrom, said moving and ejecting means including coating relatively movable rotary conveyor devices arranged in spaced apart relation at the bottom of said casing-chamber to rotate about upright parallel axes at the opposite sides of said casing for receiving the cuttings, said conveyor devices having upstanding eccentric portions arranged to move horizontally in out-of-step relation and means for rotating said devices for causing said eccentric portions to move the cuttings received by said conveyor devices rearwardly between said devices in said casing-chamber.

7. A cuttings-conveying mechanism adapted for association with a coal cutting machine of the kind having orbitally moving kerf cutting devices guided for circulation in a cuttings-receiving chamber within the frame of the machine, comprising a casing attachable to the machine frame of the coal cutting machine and having a chamber for receiving the cuttings brought back from the kerf by the cutting devices and discharged from said machine-frame chamber, and cuttings-moving and ejecting means in said casing-chamber for moving the cuttings rearwardly therein and for positively ejecting the cuttings therefrom, said moving and ejecting means including a horizontal disk arranged at the bottom of said casing-chamber to rotate about an upright axis, said disk receiving the cuttings in said casing-chamber and having an upright eccentric portion for moving the cuttings rearwardly in said casing-chamber, a horizontally swingable pusher and ejector arm overlying said disk and pivotally connected at one end to said casing and at its opposite end to said eccentric portion and means for rotating said disk to cause said eccentric portion to move the cuttings received by said disk rearwardly in said casing and for swinging said arm back and forth on its pivot for causing said arm to receive the cuttings moved rearwardly by said eccentric portion and move the cuttings rearwardly in and eject the cuttings so moved from said casing-chamber.

8. A cuttings-conveying mechanism adapted for association with a coal cutting machine of the kind having orbitally moving kerf cutting devices guided for circulation in a cuttings-receiving chamber within the frame of the machine, comprising a casing attachable to the machine frame of the coal cutting machine and having a chamber for receiving the cuttings brought back from the kerf by the cutting devices and discharged from said machine-frame chamber, and cuttings-moving and ejecting means in said casing-chamber for moving the cuttings rearwardly therein and for positively ejecting the cuttings therefrom, said moving and ejecting means including a pair of horizontal disks rotatable in relatively opposite directions on upright parallel axes at the bottom of said casing-chamber for receiving the cuttings, cooperating material moving and ejecting elements mounted on said casing to move horizontally above said disks and operatively connected to the latter for actuation in out-of-step relation thereby for receiving the cuttings from said disks and means

for rotating said disks for moving the material received thereby rearwardly in said casing-chamber and for causing horizontal movement of said elements in out-of-step relation to move the cuttings received from said disks rearwardly in and eject the cuttings so moved from said casing-chamber.

9. A cuttings-conveying mechanism adapted for association with a coal cutting machine of the kind having orbitally moving kerf cutting devices guided for circulation in a cuttings-receiving chamber within the frame of the machine, comprising a casing attachable to the machine frame of the coal cutting machine and having a chamber for receiving the cuttings brought back from the kerf by the cutting devices and discharged from said machine-frame chamber, and cuttings-moving and ejecting means in said casing-chamber for moving the cuttings rearwardly therein and for positively ejecting the cuttings therefrom, said moving and ejecting means including a pair of horizontal disks arranged at the bottom of said casing-chamber to rotate in relatively opposite directions on parallel upright axes at opposite sides of said casing for receiving the cuttings, pusher arms overlying said disks and pivotally mounted at one end on said casing respectively at the sides thereof and projecting horizontally inwardly above said disks toward the opposite sides of the casing and means for rotating said disks and swinging said arms horizontally back and forth on their pivotal mountings to move the cuttings received by said disks rearwardly in said casing-chamber and eject the cuttings so moved therefrom.

10. A cuttings-conveying mechanism adapted for association with a coal cutting machine of the kind having orbitally moving kerf cutting devices guided for circulation in a cuttings-receiving chamber within the frame of the machine, comprising a casing attachable to the machine frame of the coal cutting machine and having a chamber for receiving the cuttings brought back from the kerf by the cutting devices and discharged from said machine-frame chamber, and cuttings-moving and ejecting means in said casing-chamber for moving the cuttings rearwardly therein and for positively ejecting the cuttings therefrom, said moving and ejecting means including cooperating horizontally movable conveyor arms mounted on said casing respectively at the sides thereof and projecting horizontally inwardly toward the opposite sides of said casing and means for moving said arms horizontally in out-of-step relation for causing said arms to engage the cuttings and move the latter rearwardly and eject the cuttings from said casing-chamber.

11. A cuttings-conveying mechanism adapted for association with a coal cutting machine of the kind having orbitally moving kerf cutting devices guided for circulation in a cuttings-receiving chamber within the frame of the machine, comprising a casing attachable to the machine frame of the coal cutting machine and having a chamber for receiving the cuttings brought back from the kerf by the cutting devices and discharged from said machine-frame chamber, and cuttings-moving and ejecting means in said casing-chamber for moving the cuttings rearwardly therein and for positively ejecting the cuttings therefrom, said moving and ejecting means including cooperating oscillatory conveyor devices mounted on said casing respectively at the sides thereof and extending horizontally in

11

said casing chamber toward the opposite sides of said casing and means for oscillating said devices horizontally in out-of-step relation for causing the same to engage the cuttings and move the latter rearwardly in and eject the cuttings so moved from said casing-chamber. 5

12. A cuttings-conveying mechanism adapted for association with a coal cutting machine of the kind having orbitally moving kerf cutting devices guided for circulation in a cuttings-receiving chamber within the frame of the machine, comprising a casing attachable to the machine frame of the coal cutting machine and having a chamber for receiving the cuttings brought back from the kerf by the cutting devices and discharged from said machine-frame chamber, and cuttings-moving and ejecting means in said casing-chamber for moving the cuttings rearwardly therein and for positively ejecting the cuttings therefrom, said moving and ejecting means including cooperating oscillatory conveyor devices mounted in spaced apart relation respectively at the sides of said casing and extending horizontally in said casing-chamber toward the opposite sides of said casing and means for oscillating said devices for causing the same to engage the cuttings and move the latter rearwardly through the

12

space between said devices and eject the cuttings so moved rearwardly from said casing out of the machine path.
